UNITED STATES PATENT OFFICE.

LAWRENCE F. KRIES, OF BALTIMORE, MARYLAND, ASSIGNOR TO WESTINGHOUSE ELECTRIC & MANUFACTURING COMPANY, OF EAST PITTSBURGH, PENNSYLVANIA, A CORPORATION OF PENNSYLVANIA.

DOUBLE-THROW SWITCH.

1,414,421.

Specification of Letters Patent. Patented May 2, 1922.

Application filed August 17, 1917. Serial No. 186,763.

To all whom it may concern:

Be it known that I, LAWRENCE F. KRIES, a citizen of the United States, residing at Baltimore, in the State of Maryland, have 5 invented certain new and useful Improvements in Double-Throw Switches, of which the following is a specification.

This invention relates to electric service boxes, and more particularly to a combined 10 switch and fuse box of the general type shown in my prior Patent No. 1,224,880, granted May 1, 1917.

The primary object of the present invention is to provide a switch box of this character equipped with a double-throw switch 15 and two sets of fuses. Such a box is especially adapted for use where two feeder circuits are to be supplied from one set of mains, or where a single feeder is to be supplied from either of two sets of mains. 20 It also has utility in circumstances where it is desirable to provide two sets of fuses between a single feeder and a single main so arranged that either set may be thrown into the circuit.

25 Among other objects of the invention are to so construct the box as to render it absolutely safe under all conditions, and to positively prevent the possibility of the unauthorized taking of current therefrom. I also contemplate certain improved structural features, by virtue of which the parts 30 of the box may be more readily assembled and the various switch contacts conveniently connected to the respective conductors. Additional objects and advantages of the 35 invention will be apparent from a detailed description thereof.

In order that the invention may be clearly understood, reference is had to the accompanying drawings, forming a part of this 40 specification, and in which,

Fig. 1 is a central, longitudinal section through my improved switch box, showing the switch in one of its operative positions; 45 Fig. 1^a is a view of a stoppage screw which I may employ;

Fig. 2 is a view similar to Fig. 1, but showing the switch in neutral position;

Fig. 3 is a sectional plan of the box, taken 50 on the line 3—3 of Fig. 1;

Fig. 4 is a transverse section, substantially on the line 4—4 of Fig. 2, looking in the direction of the arrow;

Fig. 5 is a fragmentary side elevation of the switch and associated parts, the casing 55 being broken away;

Fig. 6 is a perspective view of the bottom of the box, or base plate;

Fig. 7 is an end elevation of the box, showing means for coupling a cable conduit 60 thereto;

Fig. 8 is a perspective view showing a slightly modified construction of one of the sector-shaped end plates forming part of the switch structure;

Fig. 9 is a fragmentary, sectional view, similar to Fig. 1, showing a slightly modified arrangement.

Fig. 10 is a sectional elevation of the double-throw switch member, showing a modified construction in which fuses are interposed in the switch blades;

Fig. 11 is a sectional elevation, on an enlarged scale, taken on the line 11—11 of Fig. 10, looking in the direction of the arrow; 75 and,

Figs. 12, 13, and 14 are diagrams illustrating various circuit arrangements with which my improved switch-box can be employed.

Referring to the drawings in detail, and particularly to Figs. 1 to 6 thereof, my improved box consists of a base plate or bottom 1, and a casing 2. These may be of cast or sheet metal and are preferably free from seams, joints, or projecting bolts other than those shown in the drawing and now to be described.

The casing or container is divided, by means of the partitions 3 and 4, into a central compartment A, containing the switch, and two end compartments B and C, containing the fuses. As shown in Figs. 1 and 2, the lower part of the partitions 3 and 4 is preferably formed of strips 5 and 6, of insulating material, as in my prior patent 80 above referred to. The switch compartment A is provided with a door D, and the fuse compartments B and C are provided with doors E and F, respectively.

Referring now to Fig. 6, the base plate 1 100 is formed with upstanding marginal segments 7 and 7', and similar end segments 8 and 8'. These segments are preferably formed at the factory with weakened or partially removed portions, as indicated at 105 7^b, such portions adapted to be knocked out

when the box is installed to form openings such as 7^a—8^a, for the reception of the conduits. Similar weakened portions 9 are preferably formed in the bottom plate itself 5 so that conductors can be brought in from the back, if desired, as is the common practice in junction boxes.

The plate 1 is provided with a series of holes 10 to receive fastening screws, by 10 means of which it may be attached to a wall, and is formed at its ends with perforated lugs or feet 11 for the same purpose.

The electrical apparatus contained in the box is mounted upon a base X of insulating 15 material, such as slate, and in order to support this base a suitable distance from the bottom plate 1, so as to permit electrical connections to be made on the back thereof, perforated bosses 12 are preferably formed 20 on or secured to the plate 1, as shown. The base X rests upon these bosses and is secured in position by means of screws 19 passing through the same.

The plate 1 is further provided with up- 25 standing perforated lugs 13 at its edges, such lugs being adapted to fit on the inside of the walls of the casing 2, and the casing is attached to such lug by means of screws 20 put in from the inside, as shown in Figs. 30 1 and 3.

Several methods of attaching the cable 35 conduits to the box may be employed. As shown in Fig. 7, and at the left of Figs. 1 and 6, the method which I prefer to employ 40 is as follows: The conduit 16, which in this instance, consists of a metal pipe, is threaded at its end and has a collar 15 screwed thereon. This collar is larger than the opening 8^a in the segment 8 and is held 45 against the outer face of such segment by means of a yoke 14, slipped over the end of the pipe before the collar is attached and secured to the segment 8 by means of screws 17, passing through holes 18 in the segment 50 and inserted from the inside.

Another method is similar to that shown 55 in my patent above referred to, and is illustrated at the right of Fig. 1. This consists in providing a tapering threaded nipple 22, which is secured into the opening in the segment 8'. The end of the conduit 21, which in this case may be a lead pipe, is expanded over the end of the nipple 22 and is secured in position by means of a yoke 23, held on by screws from the inside.

Openings 2' are formed in the sides and ends of the casing, shaped to conform with the segments 7 and 8, and arranged to overlap the edges of such segments. Inwardly 60 projecting tougues 2^a are formed integral with the walls of the casing and are adapted to engage the inside of the upper edges of the segments 7 and 8.

Mounted upon the base X in the middle 65 of the compartment A is a double-throw

switch S, shown as a three-pole switch. This switch consists of the blades 24 and 25, disposed at an angle to each other, as shown in Figs. 1 and 2, and pivoted at 26 to clips 27, secured to the base X. The outer ends 70 of the blades 24 and 25 are connected by bars 28 and 29, respectively, formed of some suitable insulating material, and the ends of these bars are themselves secured to sectors 30 and 31, which serve to hold the 75 parts of the switch rigidly together. The sectors 30 and 31 are themselves pivoted at 32 and 33, respectively, to brackets 34 and 35, mounted upon the base X, the pivots 32 and 33 being in line with the pivots 26 so 80 that the whole switch structure turns together about the common axis.

The switch blades 24 are arranged to engage and bridge clips or contacts 36 and 38, while the switch blades 29 are arranged 85 to engage contacts 37 and 39, all of these contacts being mounted upon the base X. Associated with the contacts 38 and 39 are binding posts 40 and 41, respectively, to which the conductors which run underneath 90 the base are connected. Extending under the partitions 4 and 3 are conducting strips 42 and 43, respectively, connecting the contacts 36 and 37 with fuse clips 44 and 45, respectively. Other sets of clips 48 and 49 95 are provided and are associated with binding posts 50 and 51 to which the conductors are attached. Suitable fuses 46 and 47, here shown as being of the cartridge type, are held in the clips 44—48 and 45—49, respectively. In order to indicate to the operator 100 the position of the switch a target or dial plate 53 is attached to one of the sectors, such as 30, and has on its outer face the words "On-Neutral-On," and the wall of 105 the casing 2 is provided with a window 52, through which these words may be read.

In order to actuate the switch manually, operating means extending outside of the casing are provided. Such means consist 110 of a pair of bail-shaped members 54 and 55, preferably formed of relatively thin, flat strips of metal set edgewise and having at their ends the handle portions 54^a and 55^a, respectively. These bails are slidably 115 mounted in the end walls of the casing 2 and in the partition walls 3 and 4 and are united at their ends in the central compartment A by means of joints k.

Adjacent each compartment B and C, the 120 legs of the bails 54 and 55 are cut away to form elongated notches 56 and 57, respectively. These notches have curved ends and co-operate with tail pieces 60 and 63 of the doors E and F, which are pivoted at 58 125 and 61, respectively. The doors E and F are flat, as indicated at 59 and 62, respectively, but may be provided at their ends with up-standing flanges 70 and 74, respectively, adapted to lie flat against the inside of the 130

end walls of the casing. These upstanding flanges may have a perforation 71 registering with a similar perforation 72, formed in the wall of the casing and adapted to receive 5 the wire of a seal 73, as shown in Fig. 2. The doors E and F are provided with handles or knobs 64 and 65, respectively. The bails 54 and 55 are provided in either one or both legs with a series of holes 75—10 76—77—78—79 and 79^a, for a purpose hereinafter described. The connection between the bails 54 and 55, which together constitute an operating member, and the switch S consists of a pair of shouldered bolts 80 and 15 81, respectively, fastened in the legs or sides of the bails and adapted to engage notches 82 and 83, respectively, formed in the upper edges of the sectors 30 and 31.

A pair of locking devices in the form of 20 ordinary sliding bolts 84—85 are secured to the partition walls 3 and 4 in the switch compartment in such position as to be capable of engaging the holes 75—79, etc., in the operating member. A stop screw 86 (Fig. 25 1^a) is also adapted to be set into any desired one of these holes so as to limit the movement of the operating member, as desired. This may be done for the purpose of 30 insuring the stoppage of the switch in neutral position, as shown in Fig. 2, or for other purposes.

The door D of the switch compartment 35 consists of a flat sheet of metal 87, preferably having a glass window 88 set therein and pivoted at 89 to the casing. The door may be provided with an upstanding flange 90, adapted to receive a seal 91, and is also equipped with a lock and key 92—93, so that 40 access to the switch compartment by unauthorized persons can be prevented.

Means are also provided for locking the operating member so as to maintain the switch in any desired position. As shown in 45 the drawings, this is accomplished by arranging perforated lugs 94—95 at each end of the box adjacent the respective bail members. When one of the holes, such as 78, registers with the opening 96 in one of the lugs, such as 94 or 95, a padlock 97 is inserted in the aligned openings and the parts 50 thus locked in position.

As shown in Fig. 9, I may provide binding posts such as 98 in connection with the 55 conducting strips 42 and 43. These binding posts, as indicated in Fig. 12, 13, and 14, are for the purpose of attaching the meter and ground connections. It is also often desirable in a three-wire system, where the neutral is grounded, to make the neutral 60 "solid" so that the ground connection cannot be interrupted. For this purpose, I provide a conducting strip 99, embedded in a groove in the back of the base X, as shown in Fig. 9, and attached to the bottom of the 65 clips ordinarily used to support the fuse 47.

With this arrangement, it will be seen that it is immaterial whether the fuse is absent or present.

Figs. 12, 13, and 14 illustrate three different applications of my improved switch and fuse box to the control of commercial circuits. In Fig. 12, is shown a feeder system 70 100, adapted to supply current to either one of two load circuits or mains 101 and 102. The switch contacts 38 and 39 in this instance are joined by means of conductors 103, arranged on the back of the base, and the feeder conductors are attached to these contacts. When the switch is in one "on" 75 position, current is supplied through the switch blades 24 to the mains 101, and when it is in the other "on" position, current is supplied through the switch blades 25 to the load 102. When in neutral position, both 80 circuits are open.

Fig. 13 illustrates another common situation in which two sets of feeders 104—105 are arranged to supply a single load circuit 106. This is the case where a building is supplied with current either from its private 90 plant or from the city mains and a double-throw switch is employed for throwing over from one source of current to the other. The binding posts 50 and 51 are connected on the back of the base by means of conductors 95 107, and the load wires 106 are also connected to these binding posts. This is the arrangement of circuits corresponding with the location of conductors shown in Figs. 1, 2, and 4.

In Fig. 14 is illustrated an arrangement in which a single feeder 108 supplies current to a single load circuit 109, but in which it is possible to feed the current through either one of two sets of fuses by throwing the 105 switch from one position to the other, as will be obvious.

In installing my improved box in a building, the method hereinafter described is followed. The plate 1 is first mounted upon the wall or other suitable support and secured in position by means of screws. The conduits such as 16 and 21 are then attached to the respective segments, such as 8 and 8', and the several conductors laid out upon the plate 1 and their ends bent up at points approximately corresponding with the location of the holes through the base X. The base with the switch and fuse mounted thereon is then placed in position over the plate 1, the free ends of the conductors being threaded through the respective holes and attached to the proper binding posts. The base is then firmly anchored by means of the screws 19. After the electrical connections have thus all been made, the casing 2 is placed in position over the base, the bolts 80 and 81 being slipped into the respective notches 82 and 83. It will be seen that the lower edge of the casing 2 embraces the lugs 130 125 110 115 120 125

13 and segments 7 and 8 so that when in position there are no projecting parts other than the feet 11, as shown in Fig. 7.

As in my prior patent, it will, of course, 5 be understood, that in the present invention, it is impossible to open a fuse compartment whenever the switch is closed so as to supply current to the fuses in that compartment. In other words, referring to Fig. 1, 10 the door F of fuse compartment C is locked because the switch S is in a position to supply current through the fuses 47 in such compartment. In this position of the switch, however, the fuses in compartment B 15 are dead and the door E of this compartment is free to open. The switch compartment A is, of course, closed at all times and the switch and all live current carrying parts are inaccessible to unauthorized persons. In Fig. 2, the switch is shown in neutral position and the notches 56 and 57 are 20 so proportioned that both doors E and F are locked. It will be obvious, however, that it is possible to shift the operating member 25 slightly in either direction a sufficient distance to cause the edge of one of the notches to clear the tail piece of the corresponding door so as to permit such door to be opened without bringing the switch 30 blades 24 or 25 into engagement with either set of contacts. In this way, either set of fuses 46 or 47 can be inspected or replaced without closing either circuit.

When it is desired to use the switch so as 35 to normally operate between the neutral and one "on" position, the stop screw 86 can be inserted in one of the holes, such as 75 or 79, and this stop screw, striking against the corresponding partitions 3 or 4, will prevent 40 the switch moving past neutral position. When it is desired to use the other side of the box, this stop screw may be removed or shifted. The sliding bolts 84 or 85 are adapted to enter the holes 75, 76, 77, or 79, 45 to lock the switch in either of its closed or its neutral positions. As above pointed out, when the switch is locked in its neutral position, as shown in Fig. 2, both fuse compartments are also locked so as to prevent unauthorized tampering. This is a desirable 50 feature in cases where it is necessary to permanently interrupt the supply of current through the switch for an extended period.

In order to insure the doors E and F being closed or moved to locking position prior to the throwing of the switch, I preferably provide light helical springs 58' and 61', attached to the inside of these doors, respectively, as shown.

60 With my improved box as herein described, it is possible to construct the switch as shown in Figs. 10 and 11, with an extra set of overload or emergency fuses. Referring to these figures, it will be seen that in 65 the switch blades 24' and 25' are interposed

sections of insulation *a* and *b*, and on either side of such insulation are secured fuse clips *c*. These clips are adapted to carry cartridge fuses *e* and *f*, respectively. Such fuses are of greater capacity than the service fuses 46 and 47, but, being inaccessibly enclosed in the compartment A, serve to protect the circuit against accidents which might be caused by re-fusing the compartments B or C with excessively heavy fuses. 70 The lower ends of the clips *c* are preferably made wedge-shaped, as shown at *d*, so as to enable them to easily enter the switch contacts. 75

In some cases it may be desirable to form 80 the switch sectors as shown at 30' in Fig. 8, in which a closed slot 82' is provided in place of the open notch 82. With such a construction, of course, a different method of assembling must be employed. 85

What I claim is:

1. The combination with a casing having a pair of openings, and a separate door for closing each opening, of two sets of fuse terminals in different parts of the casing, each 90 set being accessible through one of said openings, when the corresponding door is open, supply wire terminals and live switch contacts in still another part of the casing, means for preventing access through either 95 of said openings to said line terminals and switch contacts, a movable switch member within the casing for selectively connecting said switch contacts with either of said sets of fuse terminals, and means operatively 100 related to said doors and switch member necessitating the closure of each door prior to the closing of the switch in such manner as to connect with the corresponding set of fuse terminals, and the opening of the switch 105 prior to the opening of each such door.

2. The combination with a casing divided into three compartments, of a switch in one compartment, and fuse terminals in the other compartments, said switch serving to 110 control the flow of current to said fuse terminals, doors for said fuse terminal compartments, and mechanism for actuating said switch and simultaneously controlling said doors, said mechanism comprising means for preventing each door from being opened while the switch is in position to supply current to the fuse terminals in the corresponding compartment. 115

3. The combination with a casing having 120 a central compartment, and a compartment arranged at each end thereof, provided with a door, fuse terminals in said end compartments, and a double throw switch in said middle compartment controlling the supply of current to the fuse terminals in said end compartments, and actuating mechanism for the switch operable from without the casing, said mechanism and both of said doors having interlocking parts acting to automati- 125 130

- cally lock either door in closed position when said mechanism is moved to supply current to the fuse terminals in the corresponding compartment, while permitting the other door 5 to be opened.
4. The combination with a casing having a switch compartment, and two separate fuse compartments, of a double-throw switch in the switch compartment having a "neutral" 10 and two "on" positions, fuse terminals in the fuse compartments, said switch serving when in each of its "on" positions to connect the fuse terminals in one or the other of the fuse compartments with the source of current, doors for said fuse compartments, and operating means for the switch co-operating with said doors so as to necessitate the closing of the door of either fuse compartment before the switch can be thrown to the corresponding "on" position.
5. The combination with a casing having a central and two end compartments, of a switch in said central compartment, having two "on" positions, and a "neutral" position 25 intermediate said "on" positions doors for said end compartments, and actuating mechanism for said switch, said mechanism comprising means for locking one of the doors when the switch is in either of its "on" positions, and for locking both doors when the switch is in neutral position.
6. The combination with a casing having a switch compartment and two fuse compartments, of a double-throw switch in the 35 switch compartment, and fuse terminals in the fuse compartments, switch actuating mechanism comprising a slidable member extending through all three compartments, and doors for said fuse compartments, both said doors having parts disposed in interlocking relation with said member whereby both doors are locked closed when the switch is in neutral position.
7. The combination with a casing having 45 a switch compartment and two fuse compartments, of a double-throw switch in the switch compartment, and fuse terminals in the fuse compartments, switch actuating mechanism comprising a slidable member lying partly within all three compartments, doors for said fuse compartments having parts disposed in interlocking relation with said member, and said member having a pin and slot connection with said switch whereby 55 both doors are locked closed when the switch is in neutral position.
8. The combination with a casing having three compartments, of a switch and two sets of fuse terminals adapted to be alternatively connected thereto and all disposed in separate compartments, actuating mechanism for said switch, and means whereby access to said sets of fuse terminals is so selectively controlled by the switch-actuating 60 mechanism that, when the switch is connect- ed to one set of fuse terminals, such terminals are rendered inaccessible and the other set of fuse terminals are rendered accessible.
9. The combination with a casing having three compartments, of a switch and two sets of fuse terminals adapted to be alternatively connected thereto and all disposed in separate compartments, a door for each compartment, actuating mechanism for the switch, and means whereby the doors of the fuse-terminal compartments are so selectively locked by the operation of the actuating mechanism that, when the switch is connected to one set of fuse terminals, such terminals are rendered inaccessible by the door for their respective compartment and the other set of fuse terminals are rendered accessible.
10. The combination with a casing comprising separate switch and fuse compartments, of a switch in the switch compartment, operating means for the switch projecting outside of the casing, a door preventing access to the switch compartment, and means in said switch compartment for locking said operating means against movement in its open or closed position.
11. The combination with a casing comprising separate switch and fuse compartments, of a switch in the switch compartment, operating means for the switch projecting outside of the casing, a door for the fuse compartment having a part interlocked with said operating means, another door, controlling access to the switch compartment, and means in said switch compartment for locking said operating means against movement.
12. The combination with a casing having doors, of an inaccessible double-throw switch mounted therein, two sets of fuse terminals in said casing, access to which is controlled by said doors, and the supply of current to which is controlled by said switch, means extending outside the casing for normally actuating said switch to throw it from one operative position to the other, and means inaccessible to the operator, for limiting the movement of the switch to prevent it from being thrown to one of its operative positions.
13. The combination with a casing having a pair of doors, of an inaccessible double-throw switch mounted therein, said switch having two "on" positions, and a "neutral" position intermediate said "on" positions, and actuating mechanism for said switch, said mechanism comprising means for locking one only of said doors when the switch is in either of its "on" positions or between the neutral position and either "on" position, and for locking both said doors when the switch is in neutral position.
14. The combination with a casing hav-

ing a pair of doors, of an inaccessible double-
throw switch mounted therein, said switch
having two "on" positions, and a "neutral"
position intermediate said "on" positions,
5 and actuating mechanism for said switch,
said mechanism comprising means for lock-
ing both said doors when the switch is in
neutral position, and for releasing one or
the other of said doors when the switch is
10 shifted from such neutral position toward
the respective "on" position.

15. The combination with a casing having
a switch compartment and two fuse com-

partments, a fuse in each fuse compartment,
a double-throw switch in the switch com- 15
partment for alternatively connecting the
fuses thereto and a door for each fuse com-
partment, of means for so interlocking the
doors with the switch that, when the switch
is connected to one of the fuses, the door 20
for its respective compartment is held in
closed position.

In testimony whereof I have affixed my
signature.

LAWRENCE F. KRIES.
